HAIR-WAVING APPARATUS

Jean Leclabart, Paris, France

Application May 14, 1949, Serial No. 93,312
In France August 5, 1948

4 Claims. (Cl. 132—36.2)

1

This invention relates to a new hair-waving apparatus.

In prior art strands of hair were moistened in a waving solution and then were wound individually upon mandrels or curlers. In the case of cold hair waving, the strands of hair must remain wound a considerable length of time in order to form a wave. The heating of the hair has the advantage of speeding up the process to a considerable extent but it requires expensive and complicated apparatus, the heating elements of which are heated to a comparatively high temperature, usually substantially higher than 100° C. This high temperature is often most uncomfortable and inconvenient to the operator as well as to the user, and sometimes results in burns and other damage. The use of heating clamps or similar elements which are placed over the woven strands of hair is particularly dangerous since such clamps may burn, not only the woven strands but also the scalp of the user. Attempts to avoid this danger by placing protective pads between the scalp and the strand were not completely successful since they inconvenience the winding of the strand to a considerable extent. The use of clamping elements for the same purpose was also found to be quite expensive and inconvenient.

An object of the present invention is the provision of a new device for carrying out a method of permanent waving which combines the advantageous features of both cold and hot waving, and eliminates the drawbacks of both methods.

The device which is the object of the invention makes possible a waving method by the use of which the time required for cold waving is reduced, substantially to the time necessary for hot waving, while at the same time eliminating metallic heaters and complicated heating apparatus.

The device which is the object of the invention is a heating sleeve for mounting upon a strand of hair which has been impregnated with the customary cold-waving solution and is wound upon a clamp or mandrel. This heating sleeve comprises an elongated tubular body made wholly of a plastic, flexible and elastic material provided with a longitudinal slot formed therein from one end to the other end thereof, the portion of said body located opposite said slot forming a hinge for the two lateral portions of said body located adjacent to sides of said slot, two ribs fast with said tubular body extending on opposite sides of said hinge and constituting finger supports for manipulating said sleeve, and at least one separate metallic heat accumulating body embedded in the material of said tubular body. This sleeve,

2

which has been heated to a temperature less than 100° C., supplies sufficient heat to the waving solution so as to precipitate its action and thus reduce to a considerable extent the time necessary for the waving of the hair.

The user can easily open the tube due to the provision of the longitudinal slot, and place it over the wound strand of hair, the edges of the slot pressing against each other as the result of their elasticity.

10 The elastic sleeve need not be made completely of an elastic material but may be made with a partly elastic section serving as a connection or hinge between two non-elastic portions located on opposite sides of the longitudinal slot. These non-elastic portions may be made of metal, ivory, wood or the like. The two ribs fast with the tubular body and extending on opposite sides of the hinge serve as holders for the fingers of the user to facilitate the opening of the sleeve. The metallic heat accumulating bodies embedded in the material of the tubular body of the sleeve may be metallic rods embedded longitudinally in said tubular body.

15 25 The sleeve may be heated by being immersed in a hot liquid, or by any other suitable means. Preferably, the sleeve is heated by the use of a heating container which may consist of a casing containing a double bottom which is filled with heat-insulating material such as sand, gravel or the like.

20 30 The invention will appear more clearly from the following detailed description, when taken in connection with accompanying drawings showing, by way of example, preferred embodiments of the inventive idea.

35 35 In the drawings:

Figure 1 is a section through a sleeve constructed in accordance with the principles of the present invention;

40 Figure 2 is a section through a somewhat differently constructed sleeve;

Figure 3 is a section through a third form of the sleeve;

45 Figure 4 is a section through a sleeve provided with depending leg portions;

Figure 5 is a longitudinal section through a differently constructed sleeve, along the line V—V of Figure 6;

50 Figure 6 is an end view of the sleeve shown in Figure 5;

Figure 7 is a perspective view of a differently constructed sleeve;

Figure 8 is a transverse section through the sleeve shown in Figure 7;

Figure 9 is a perspective view of a sleeve of a different form;

Figure 10 is a transverse section through a differently constructed sleeve;

Figure 11 is a transverse section through yet another sleeve;

In accordance with the embodiment shown in Figure 1 the heating sleeve consists of an inner tube 1c and an outer tube 3c, which is mounted upon the tube 1c. These tubes consisting of simple rubber tube having a slot, respectively 2 and 2c, which extends transversely along the entire length of the tube. The tubes, in lieu of rubber, may be made of any other suitable elastic material. Thus the edge portions 2b which are located on opposite sides of the slot 2c are formed of somewhat less thickness and greater elasticity than the other portions of the article so that a strand of hair wound upon a clamp, to be described hereinafter, and impregnated with a waving solution, in the usual manner, can be sufficiently firmly clamped by the members 2b, thereby avoiding the escape of heat. The outer sleeve 3c encloses only a part of the inner sleeve 1c, leaving exposed the members 2b. The sleeve 3c may be connected to the sleeve 1c in any suitable manner, such as glue, pressure or the like. It is apparent that the edges 2b will retain sufficient elasticity to conform themselves to the location of the roots of hair forming a strand which is to be covered by the sleeve.

Obviously, the arrangement may be reversed and the recesses may be formed upon the inner member.

An insert 4, which may serve as a heat accumulator, is located between the tubes 3c and 1c. In the construction shown in Figure 1 a single heat accumulator 4, which is made of metal, is set diametrically opposite the slot 2c.

The sleeve shown in Figure 2 consists of an outer member 3d enclosing an inner member 1d which is provided with a slit 2d. Two metal inserts 4a and 4b, serving as heat accumulators, are located opposite each other and substantially at right angles to the slot 2d.

It is apparent that the heat accumulators 4, 4a and 4b may be made of metal, a metal alloy or of any other suitable heat-conserving material.

These accumulators can be firmly and permanently imbedded in the device, or they may be introduced into their proper positions between the concentric tubes after having been heated, and solely for the duration of the heating operation. In accordance with the construction in Figure 3 the heating sleeve consists of a single tube 5b, the cylindrical interior of which is made eccentric in relation to that tube so that that part of the tube which is located opposite the slot 6b has a greater thickness than the remaining portions of the tube. This arrangement results in a construction which has all the advantages of the construction shown in Figures 1 and 2, namely, the portions 6c located on opposite sides of the slot 6b are sufficiently thin and elastic, while the opposed portion 5a is sufficiently thick to provide a sufficient accumulation of heat.

This portion 5a is provided with additional recesses adapted to contain a heat accumulator 8. The recesses may be located diametrically opposite the slot 6b leading to the interior 7b of the tube 5b. The accumulator 8 may be of curved shape so as to fit more conveniently into the tube 5b.

Obviously, the accumulators may be imbedded

in the tubes at the time the latter are manufactured, and may be of any suitable form. Other heat-retaining elements in granular or threaded form may be also conveniently located within the sleeve.

The sleeve shown in Figure 4 is substantially similar to the sleeve of Figure 3 in that it consists of a single tube 11 provided with a slot 13 and the cylindrical interior 12 of which is eccentric in relation to that tube, but this tube 11 has two supports or legs 13a having the form of ridges or projections which may extend along the entire length of the tube. Due to this arrangement the sleeve shown in Figure 4 is supported upon the scalp of the user, or upon the protecting pad solely along narrow surfaces. The contacting surfaces may be further diminished by providing transverse grooves upon the lower ends of the legs 13a, thereby eliminating the transmission of heat to the user. As in the construction shown in Figure 3, the tube 11 contains a heat accumulator 14. The cylindrical space 12 which is eccentric in relation to the member 11, communicates with the outside through the slot 13. The legs 13a are located on opposite sides of the slot 13.

It is apparent that numerous changes may be made in the illustrated constructions. For example, the sleeves need not be round and the longitudinal slit may be arranged at any section of the sleeve. The heat accumulating elements may be arranged transversely to the sleeve instead of longitudinally, and may consist of a plurality of elements.

By way of example, the sleeve shown in Figure 3 may be of the following dimensions: The elements 6c adjacent the slit 6b may have a thickness of 1.5 mm. The hollow space 7b may have a diameter of 8 mm. The distances between the slit 6b and the heat accumulator 8 may be equal to 10.5 mm. The heat accumulator 8 may have a maximum thickness of 1.5 mm. and may be situated at a distance of 1.5 mm. from the outer surface of the sleeve. Obviously, the length of the sleeve depends on the length of the hair-carrying clamp.

As already stated, the sleeves may be conveniently heated in a container filled with hot water. On the other hand, all other heating means may be utilized, such as a container heated by steam, gas, electricity, or hot coals, or by means having a lengthy combustion. Furthermore, the sleeves may be immersed in sand heated to a suitable temperature. The sleeves can be arranged in heating devices in such manner that they are easily accessible and may be removed from heating containers by means of pincers so as to avoid any danger of burning the fingers of the user.

It is apparent that the described sleeves are most simple in construction, light, inexpensive and easy to use. Furthermore, the utilization of these sleeves avoids the danger of damaging the hair since the temperature to which they are heated must not exceed 100° C. Finally, the described sleeves may be advantageously heated by simple and most effective means.

The Figures 1 to 4 and the hereinabove explanations are to illustrate and describe the different embodiments of the peculiar structure of the tubular body of the heating sleeve according to the invention, which sleeve also includes two ribs fast with the tubular body and constituting finger supports for manipulating the sleeve.

Figures 5 and 6 illustrate entirely a first em-

bodiment of a heating sleeve. This sleeve includes a main body 1f which is made of rubber or any other suitable plastic and elastic material. The body 1f encloses a hollow, cylindrical space 2f which is eccentric in relation to the body 1f. A longitudinal slit 3f connects the chamber 2f with the atmosphere and is located at the thinnest portion of the member 1f. A metallic body 4f is imbedded in the rubber element 1f and serves as a heat accumulator and as heat-transmitting means.

The sleeve also includes two members 15 located on opposite sides of the tube 1f and on opposite sides of the slit 3f. Each of these members consists of a metallic wire which is bent in the middle to form a loop 16 located above the body 1f and away from the slit 3f. The two ends of each of the wires 15 are inserted through the rubber body 1f at points 17 and 18, shown in Figure 5, and are bent against surfaces of the hollow space 2f to form legs 19 and 110.

It is apparent that when the user presses the two loops 16 toward each other the ends 19 and 110 will move outwardly and will pull along with them the edges of the tubular body located adjacent a slit 3f, thereby opening the slit and facilitating the mounting of the sleeve upon a wound strand of hair.

As shown in Figure 5, the heat accumulator 4b has the form of a plate which is longer than the sleeve 1f so that its ends project beyond the ends of the tube and are bent at these ends.

This arrangement has the advantage that when the sleeve is inserted into a container for heating purposes the projecting ends of the plate 4f will be brought in contact with the heated walls of the container and will readily absorb heat and transmit it throughout the sleeve. Due to this arrangement the sleeve may be readily and uniformly heated, and will be able to absorb large amounts of heat in its interior.

The sleeve shown in Figures 7 and 8 includes a rubber body 111 which is provided with a longitudinal slit 112. In this construction the opening of the tubular member 111 is caused by two members 113 and 114 consisting of thin, curved metal sheets provided with outwardly bent projecting portions 117 and 118 which can be readily engaged by the fingers of the user. The opposite ends of the members 113 and 114 are introduced into the hollow interior of the tube 111 through the slit 112, and are bent against the inner walls of the tube 111, thus forming the portions 115 and 116. It is apparent that the end portions of the tube 111, located on opposite sides of the slit 112, are enclosed by the end portions of the metallic members 113 and 114. It is further apparent that when the user moves the projections 117 and 118 toward each other the portions 115 and 116 will cause the opening of the slit 112 so that the sleeve can be conveniently placed over a clamp.

A metal plate 119 which is provided with suitable curvature is located within the hollow interior of the tube 111, and is situated against an inner surface of the tube opposite the slit 112. The plate 119, which serves as a further heat accumulator, may be supported within the tube 111 by clips 120, which are located at opposite ends of the tube 111. Obviously, the members 120 may be integral with the plate 119. It is apparent that the plate 119 in no way interferes with the opening or closing of the sleeve, or with any changes in the form thereof.

Figure 9 shows a sleeve comprising a tubular

member 121 made of rubber or other plastic and elastic material, and provided with a longitudinal slit 122. The rubber body 121 is integral with wing-shaped projections 123 and 124, which are located substantially opposite the slit 122. It is apparent that the projecting portions 123 and 124 serve as finger supports and that a pressing of the members 123 and 124 toward each other will cause the opening of the slit 122. This arrangement has the advantage that the actuating members 123 and 124 are formed at the same time that the sleeve 121 is formed. Metal rods 125 and 126, serving as accumulators of heat, are imbedded in the tube 121 at the time the latter is formed. The ends of the metal rods 125 and 126 project from opposite ends of the sleeve 121, and these projecting ends have a somewhat larger diameter than the main body of the rods. It is apparent that the rods 125 and 126 extend parallel to each other in the course of the use of the sleeve, so that the sleeve will be of proper form, and the edges located opposite the slit 122 will remain parallel to each other despite the deformations to which the sleeve may be subjected in the course of its use.

Figure 10 shows a sleeve having a body 129 which is integral with wing-like projections 123a and 124a, located substantially opposite the slit 122a. In this construction the heat-accumulating means consists of two curved plates 127 and 128, situated opposite each other within the tubular member 129, and essentially at right angles to the slit 122a. As shown in Figure 10, the plates 127 and 128 are maintained in place by lips or projections 127a and 128a, respectively, which are bent around the outer edges of the body 129.

In the construction shown in Figure 11 the metal heat accumulators 131 and 132 have replaced the thin portions of the rubber tube, and are located opposite each other, forming a slot 122b. The main body 130 of the sleeve consists of rubber, and is located directly opposite the slot 122b. The member 130 may be made integral with finger-engaging projections 123b and 124b. Rods 123c and 124c may be located within these projections. It is thus apparent that in this construction the sleeve consists of three parts, namely, two metal portions 131 and 132, which form the jaws of the sleeve, and an elastic center portion 130, which serves as a hinge between the jaws. The jaws 131 and 132 may be conveniently imbedded in the rubber member 130 by means of portions 131a and 131b, which are imbedded in the rubber member 130.

In all constructions hereinbefore described the jaws are located symmetrically on opposite sides of the slit, and the portion serving as a hinge is located opposite this slit. These constructions may be replaced by a construction wherein the hinge-like portion is shifted in relation to the slit and wherein the jaws on opposite sides of the slit are of unequal length.

Before utilizing the sleeves described, the user divides her hair into strands which are impregnated with any suitable waving solution and winds the strands of hair upon one clamp. In the meantime heat sleeves of the type shown in Figures 1 to 11 are heated in an adequate container to a temperature which should be less than 100° C. The user may apply one protective pad upon each wound strand of hair, so that the pad is located upon the scalp of the user and between the scalp and the clamp. Thereupon, the heated sleeves are removed from the container and are

75

placed over the wound strands in the manner previously described. The use of the heated sleeves makes it possible to impart a permanent wave in a time period of fifteen minutes or less to hair impregnated with a cold waving solution. Thus, the duration of the waving process is diminished by a matter of hours to that of minutes. When the waving process is completed the sleeves are removed from the wound strands and then the protective pads are withdrawn from the head, whereupon the hair is unwound from the clamps.

It is apparent that the illustrations shown above have been given solely by way of illustration, and not by way of limitation, and that they are subject to many variations and modifications. All of such variations and modifications are to be included within the scope of the present invention.

What is claimed is:

1. In the art of hair waving, a heating sleeve for mounting upon a wound strand of hair, said sleeve comprising an elongated tubular body made wholly of a plastic, flexible and elastic material provided with a longitudinal slot formed therein from one end to the other end thereof, the portion of said body located opposite said slot forming a hinge for the two lateral portions of said body located adjacent to sides of said slot, two ribs fast with said tubular body extending on opposite sides of said hinge and constituting finger supports for manipulating said sleeve, and at least one separate metallic heat accumulating body embedded in the material of said tubular body.

2. In the art of hair waving, a heating sleeve for mounting upon a wound strand of hair, said sleeve comprising an elongated tubular body made wholly of a plastic, flexible and elastic material provided with a longitudinal slot formed therein from one end to the other end thereof, the portion of said body located opposite said slot forming a hinge for the two lateral portions of said body located adjacent to sides of said slot, said tubular body being formed with two ribs integral with said body and extending on opposite sides of said hinge and constituting finger supports for manipulating said sleeve, and metallic rods embedded longitudinally in said tubular body and constituting heat accumulating bodies.

3. In the art of hair waving, a heating sleeve for mounting upon a wound strand of hair, said

sleeve comprising an elongated tubular body made wholly of a plastic, flexible and elastic material provided with a longitudinal slot formed therein from one end to the other end thereof, the portion of said body located opposite said slot forming a hinge for the two lateral portions of said body located adjacent to sides of said slot, two ribs fast with said tubular body extending on opposite sides of said hinge and constituting finger supports for manipulating said sleeve, and at least one separate metallic heat accumulating body embedded in the material of said tubular body, and having its ends projecting beyond the ends of said tubular body, said projecting ends of said metallic heat accumulating body being adapted to be brought in contact with the heated walls of a container when the sleeve is inserted into said container for heating purposes.

4. In the art of hair waving, a heating sleeve for mounting upon a wound strand of hair, said sleeve comprising an elongated tubular body made wholly of a plastic, flexible and elastic material provided with a longitudinal slot formed therein from one end to the other end thereof, the portion of said body located opposite said slot forming a hinge for the two lateral portions of said body located adjacent to the sides of said slot, and at least one separate metallic heat accumulating body embedded in the material of said tubular body, the inner cylindrical space formed in said tubular body being eccentric in relation to said tubular body, the thickness of said body being the smallest in the portions adjacent said slot.
